UNITED STATES PATENT OFFICE.

FRED ANDERSON, OF WARREN, PENNSYLVANIA.

ATTACHMENT FOR LUBRICATORS.

No. 806,514.

Specification of Letters Patent.

Patented Dec. 5, 1905.

Application filed August 28, 1905. Serial No. 275,947.

To all whom it may concern:

Be it known that I, FRED ANDERSON, of Warren, in the county of Warren and State of Pennsylvania, have invented a new and useful 5 Improvement in Attachments for Lubricators, of which the following is a specification.

My invention relates to an improvement in attachments for lubricators or oil-cups for supplying lubricant to machinery, and particularly to the interior of the cylinders of 10 gas and steam engines or other places where the lubricating liquid is subject to the pressure of the fluid employed in operating the engine.

15 I will now describe my invention so that others skilled in the art may manufacture and use the same, reference being had to the accompanying drawings, forming part of this specification, in which—

20 Figure 1 shows in section my improvement applied to an ordinary form of oil-cup for supplying oil to the interior of the cylinder of a gas-engine. Fig. 2 is a cross-section on the line II II of Fig. 1.

25 Like symbols of reference indicate like parts in each view.

In the drawings, 2 represents the oil-reservoir of the oil-cup. 3 is an orifice leading therefrom and communicating with the oil- 30 discharge opening 4, controlled by the valve 5.

6 is the sight-tube chamber, provided at its lower end with an extension 7, screwing into the coupling 8. Connected to the lower extremity of the coupling 8 is a sleeve 9, having a central oil-duct 10 therethrough. At the bottom of the sleeve 9 is an extension or shoulder 11. Extending through the oil-duct 10 is a wire or rod 12, having a hooked upper end for holding the same in place. Connected to the lower end of the rod or wire 12 is a cup 13, which extends under and surrounds the extension or shoulder 11. The sleeve 9 is screw-threaded at its lower end, so that it may be screwed into the side of the 45 cylinder (represented at 14) or other place where it is desired to use the same.

The operation is as follows: The valve is adjusted so that the desired amount of oil will be fed through the opening 4. The oil 50 thus fed flows down through the sight-tube 6 and into the passage 10, through the sleeve 9, fills the cup 13, and overflows therefrom into the cylinder 14. If for any reason the

gases in the case of an explosive-engine or the steam in a steam-engine gain access to 55 the space 15 in the cylinder-wall surrounding the cup 13, the immediate effect is to force the cup against the shoulder 11 and cut off entirely all communication with the oil-supply above said cup. This prevents access of 60 the explosive or exploded gases to the oil passages and reservoir and obviates all danger of the oil being spattered by the gases against the sides of the sight-tube and interfering with the inspection of the oil-supply 65 by the engineer. It also at the same time prevents blowing of the gases into the oil-reservoir 2, which is a frequent cause of leakage in the same.

The advantages of my invention will be appreciated by those skilled in the art. It is extremely simple and inexpensive and may be applied to any ordinary form of oil-cup.

I claim—

1. An attachment for lubricators adapted 75 for connection to the lubricator and to the part to be lubricated, and having an oil-passage therethrough, and a cup at the bottom of said passage and loosely connected to said attachment.

2. An attachment for lubricators adapted for connection to the lubricator and to the part to be lubricated, and having an oil-passage therethrough, there being a shoulder extending from the lower end of said attachment, a cup surrounding said shoulder, and a rod connected to said cup and extending into said passage.

3. An attachment for lubricators adapted for connection to the lubricator and to the 90 part to be lubricated, and having an oil-passage therethrough, there being a shoulder extending from the lower end of said attachment, a cup surrounding said shoulder, and a rod connected to said cup and extending 95 through said passage and having a hook at its upper end by which the rod is suspended in said passage.

4. In combination, a lubricator having a screw-threaded lower end, a coupling having 100 its upper end internally screw-threaded for attachment to said screw-threaded lower end of the lubricator and having also an internally-screw-threaded lower end, a sleeve with its upper end screwing into said coupling and 105 its lower end screw-threaded for attachment

to a cylinder, said sleeve having a shoulder
extending from the lower end thereof, a cup
surrounding said shoulder, and a rod con-
nected to said cup and extending through an
oil-passage in said sleeve and having a hook
at its upper end by which the rod is loosely
suspended in said passage.

In testimony whereof I have hereunto set
my hand.

FRED ANDERSON.
